UNITED STATES PATENT OFFICE.

ARTHUR STUART JOHNSON, OF CONGLETON, ENGLAND, ASSIGNOR TO HUGH C. EDMISTON, OF NEW YORK, N. Y.

DESIGN FOR A PLATE OR SIMILAR ARTICLE.

48,824.

Specification for Design.

Patented Apr. 4, 1916.

Application filed February 17, 1916. Serial No. 78,998. Term of patent 3½ years.

To all whom it may concern:

Be it known that I, ARTHUR STUART JOHNSON, a subject of the King of Great Britain and Ireland, residing at Congleton, Cheshire, England, have invented a new, original, and ornamental Design for a Plate or Similar Article, of which the following is a specification, reference being had to the accompanying drawing, forming part thereof, in which the figure is a plan view of a plate, illustrating my new design.

I claim:

The ornamental design for a plate or similar article as shown.

In testimony whereof I affix my signature in presence of two witnesses.

ARTHUR STUART JOHNSON.

Witnesses:

R. V. DOBSON,
J. H. COPESTAKE.
